UNITED STATES PATENT OFFICE.

HENRY A. BERQUIST, OF ST. CROIX FALLS, WISCONSIN.

RAIL-FASTENER.

1,201,012.

Specification of Letters Patent.

Patented Oct. 10, 1916.

Application filed March 15, 1916. Serial No. 84,814.

To all whom it may concern:

Be it known that I, HENRY A. BERQUIST, a citizen of the United States, and a resident of St. Croix Falls, in the county of Polk 5 and State of Wisconsin, have invented certain new and useful Improvements in Rail-Fasteners, of which the following is a specification.

My invention relates to means for fastening the rails of railway tracks to the ties, as a substitute for the unreliable spikes, and is adapted for use with the conventional ties or with the ties shown and described in Letters Patent of the United States issued 15 to me on the 7th day of July, 1914, No. 1,102,857.

My invention is fully described in the following specification, of which the accompanying drawings form a part, in which 20 like characters refer to like parts in each of the views, and in which:

Figure 1 is a perspective view of my invention in operative position at one end of a tie, the rail being shown in section; Fig. 25 2 is a section taken on the line 2—2 of Fig. 1; Fig. 3 is a fragmentary section taken on the line 3—3 of Fig. 1; and Fig. 4 is a perspective view of a detail.

Referring to the drawings, 5 represents 30 a tie of conventional form, 6 the usual metal cap plate thereover, 7 one of the rails, and 8 and 9 the base flanges thereof.

The rail 7 is held in place by two fasteners 10 arranged upon opposite sides of the 35 tie 5, each of said fasteners consisting of a plate recessed at 11 to form a hook member 12 and a vertical member 13 spaced apart a distance approximating the width of the bottom of the rail, whereby the hook member 12 will overlie the base flange of the rail, the fasteners 10 being identical in structure 40 but reversed, end for end, upon opposite sides of the tie.

The hook member 12, as illustrated, rests 45 upon the base flange 8 upon the near side of the tie 5 whereas the hook member 12 of the fastener on the far side of the tie rests upon the base flange 9, thereby holding both flanges to the tie, or to the plate 6 interposed 50 between rail and tie, the vertical members 13 of the two fasteners preventing lateral movement of the rail.

Each fastener carries a projecting member 14 corrugated upon its outer surface, as

shown at 15, and provided with a vertical 55 slot 16, and each fastener also carries a projecting member 17 downwardly and outwardly beveled on its outer surface, as shown at 18 and provided with a vertical slot 19, the sides of the slots 16 and 19 being 60 parallel.

The fasteners 10 are held together by means of bolts 20 of identical form and having, each, a square shank 21, a head 22 set at an angle to the axis of the bolt, a body 65 member 23 of cylindrical form, and a screw threaded outer end 24, the angle of the heads 22 with respect to the axes of the bolts being the equivalent of the angularity of the beveled projections 17 with respect to the 70 lower surfaces of said fasteners.

In installing my fasteners, the tie is bored for one of the bolts 20, as shown at 25, Fig. 3, and one of the bolts 20 is then passed through the slot 19 of the inclined member 75 17 of one of the fasteners, then through the bore 25 of the tie, and then through the slot 16 of the corrugated projection 14 of the other or complementary fastener, after which a corrugated washer 26 is placed upon the 80 bolt end with the corrugations engaged with those of the projecting member 14 thereunder, and a nut 27 is then screwed upon the bolt end and tightened.

The position of the bore 25 is fixed so that 85 the projecting members 14 and 17 on one side of the rail will extend beyond the end of the tie, as clearly shown in Fig. 1, to clear the slots 16 and 19 from the end of the tie and, when the first bolt has been secured in 90 place, the second bolt 20 is passed through the slot 19 of the fastener on the near side of the tie, through a distance tube 28, and through the slot 16 of the fastener on the far side of the tie, after which a corrugated 95 washer 26 is placed on the bolt with the corrugations thereof engaged with those on the adjacent projecting member 14, and a nut 27 screwed on the end of this bolt, the fasteners now being assembled.

The vertical position of the bolt hole 25 is such as to occupy a position approximately midway of the lengths of the respective slots 16 and 19, and the corrugated washer 26 on the far side of the tie is vertically adjusted in desired relationship with the respective corrugated projecting member 14 before the nut 27 bearing thereon is 100 105

tightened, and the beveled projecting member 17 on the near side of the tie is driven down until the corresponding hook member 12 bears firmly on the base flange 8, after 5 which the nut 27 is tightened.

The nut 27 on the bolt at the end of the tie is also loose until the vertical adjustment of the corrugated washer thereat is attained and the respective beveled projecting member 17 is driven down to engage the hook member 12 on the far side of the tie with the base flange 9, after which this nut 27 is tightened, and the distance tube 28 is made of such a length as not to prevent the binding engagement of the fasteners with the tie but to prevent bending the projecting members 14 and 17 toward each other when the nut at the end of the tie is tightened. Because of the bevel on the members 17, these 20 ends of the fasteners cannot work upwardly and, because of the corrugations 15 on the members 14 and on the washers 26, no vertical movement of these washers is possible with respect to the said members 14, after 25 the desired vertical adjustment has been attained.

My fasteners are quickly and easily installed and entirely avoid the use of spikes which work loose in the movement of trains 30 on the rails, and through the decay of the wood of which the conventional tie is composed. Because of the fact that the fasteners at opposite sides of the tie are identical, no mistake can occur in the installation 35 thereof and, because of the square shank 21 of the bolts 20, no rotation of the bolts can occur, the inclined heads 22 likewise resisting any bolt rotation, although the function of the said heads is to prevent upward movement 40 of the respective ends of the fasteners.

My invention is very simple, though highly efficient, is very economical in construction and installation, and is well adapted for the purpose for which it is designed, 45 and, while I have shown certain preferred structural details, it will be evident that changes may be made thereover provided such changes do not depart from the spirit of the invention and come within the scope 50 of the following claims.

Having fully described my invention,

what I claim as new, and desire to secure by Letters Patent, is:—

1. A fastener, for use with a railway rail and tie, comprising a plate at each side of 55 said tie provided, each, with a hook member resting on the base flange of the rail and with a vertical member resting against the opposite base flange on the outer edge thereof, means for clamping said plates in position, and means resisting movement from the adjusted position.

2. A fastener, for use with a railway rail and tie, comprising a plate at each side of 65 said tie provided, each, with a hook member resting on one base flange of the rail and with a vertical member resting against the edge of the opposite base flange of said rail, means for clamping said plates in position, and means for adjusting said plates with respect to said rail and tie.

3. A fastener, for use with a railway rail and tie, comprising a plate at each side of 75 said tie provided, each, with a hook member resting on one base flange of said rail and with a vertical member resting against the edge of the opposite base flange of said rail, each of said plates having a beveled member at one end and a corrugated member at 80 the other end, a bolt at each end of said plates clamping the same to said tie, said bolts having, each, an inclined head bearing upon the beveled member of the respective plate, and a nut at its other end, and a corrugated washer interposed between the respective nuts and corrugated plate members.

4. As an article of manufacture, for use with a railway rail and tie, a plate having a recess in the upper side thereof of a length approximating the width of the base of a 90 rail, a hook member at one side of said recess, a vertical member at the other side of said recess, a slotted projecting member at one end the outer surface of which is corrugated, and a slotted projecting member 95 at the opposite end the outer surface of which is downwardly and outwardly inclined.

HENRY A. BERQUIST.
